BROOCH ASSEMBLAGE

Marcel Boucher, Eltingville, Staten Island, N. Y.

Application November 1, 1935, Serial No. 47,773

7 Claims. (Cl. 63—20)

My invention relates to brooch assemblage.

More particularly, my invention is directed to a brooch assemblage comprising a brooch base member provided with pin or equivalent means for securing to the material of a garment, such brooch assemblage comprising a set, usually a pair, of clip members, each clip member comprising a clip back member upon which the ornamental design is mounted and a clip base member hinged-
ly related to its associated clip back member. Embodiments of my invention may be utilized as a brooch assemblage, that is, the clip members optionally may be assembled with the brooch base member as a unit or any clip member, singly or plurally, may be disassociated from the brooch base member and worn individually or as a set.

The present invention is most particularly directed to a brooch base member comprising spaced extensions respectively provided with locking recesses respectively cooperating with lugs or equivalent carried by the individual clip members, which lugs are lodged and maintained lodged in locking relation to the locking recesses by the resilient means of the individual clip members.

My brooch base member comprises, in preferred form, a body formed of a bar portion and a thereto transversely extending portion, to which latter extensions, usually a pair of extensions for each clip member, such extensions being provided with locking recesses and serving to receive and securely retain the clip members in assembled positions.

Further features and objects of the invention will be more fully understood from the following detail description and the accompanying drawing, in which

Fig. 1 is a front elevation of a two-clip type of brooch adapted to embody my invention.

Fig. 2 is a rear elevation of Fig. 1, of the assemblage on the enlarged scale.

Fig. 3 is a sectional view taken on line 3—3 of Fig. 2.

Fig. 4 is an exploded view in perspective, illustrating a manner of assemblage of a brooch base member and a clip base member and clip back member, pursuant to my invention.

Referring to the drawing, Fig. 1 illustrates a two-clip type of brooch 10, the pair of indicated clips 11, 12, being adapted to be mounted upon an assembly brooch base member. Ornamentation of the respective clips is optional, the individual ornamental design of the clips 11, 12, being respectively mounted upon appropriate parts described more fully hereinafter, to afford

ready secured assembly of the respective members relative to the brooch base member, and to afford ready disassembly of the clip members individually to permit the same to be worn by the user either individually or as a pair or set. 5 Therefore, the particular ornamentation design or designs indicated in the drawing serve purely for illustrative purposes.

The brooch assembly may be secured to the material of a garment of the wearer in any suitable way, usually by means of a safety pin, indicated at 13, appropriately mounted as by means of a hinge member 13a and a suitable safety catch 13b.

Pursuant to the present invention, the brooch base member, indicated generally at 14, comprises a body portion essentially a bar and transversely extending portion, to which is secured, advantageously integral therewith, extension means in number and arrangement corresponding to the number of the clip members. In the instanced illustration of two clip members 11, 12, two such extension means are provided and, as shown, in the form of a pair of extensions 14b, 14c, for each clip member. As shown, the extension 14b includes a convergently tapered terminal portion 14d, extending preferably downwardly as viewed in Figs. 2 and 4, the purpose of which appears more fully hereinafter. The extension 14b, as shown, further comprises a recess 30 14e serving as a locking recess, as will appear. The extension 14c, as shown, includes a free terminal portion 14f tapering and extending in the direction corresponding to the free terminal portion 14d of the extension 14b, and also a locking recess 14g. The stated portions of the brooch base member 14 are readily produced by blanking and forming, of suitable material, advantageously metal.

Cooperating with the stated construction of 40 the brooch base member, each clip member comprises a clip base member, indicated generally at 15 and as clip back member, indicated generally at 16. Each clip base member 15 comprises, in essentials, a body portion 15a, an upstanding element or portion 15b, and opposingly disposed extensions 15c, and hinge means such as the upstanding apertured hinge lugs 15d. The ornamentation or design is secured, as by soldering, welding, etc., to the clip base member 15. 50

Each clip back member 16 comprises, in essentials, a body portion 16a; further, locking lugs 16b opposingly related to one another and extending in direction and spatially related to one another in coordination with the stated locking re- 55

cesses 14e, 14g, as will appear. Each clip back member 16 further comprises resilient means cooperating with the stated upstanding element or part 15b, advantageously had by saw-cutting, blanking, etc., kerfs as indicated in 16c. Each clip back member 16 further comprises pointed elements or parts 16d, for engaging the material of a garment or the like, when the clip is disassociated from the brooch base member 14 and worn individually or as a pair or set. The stated kerf, or equivalent resiliency provided means, affords dually the central tongue resilient portion 16f, a pair of pintle-provided elements 16e for association with the stated apertured hinge ears 15d, 15d, the pintles thereof being inserted relative to the apertures of the hinge lugs 15d, 15d, respectively by pressing the pintle-provided elements 16e, 16e, toward one another and releasing upon register of the respective pintles in the respective apertures of the hinge ears 15d, 15d. The assembly of the respective clip members relative to the brooch base member, as now appears, is had by passing the extensions 14b, 14c, respectively toward and upon the upper faces, see Fig. 4, the continuation of such movement causing the respective lugs 16b to ride upon the arcuate terminals 14d, 14f, until the stated lugs 16b, 16b, are received and lodged within the locking recesses 14e, 14g. The assembly of the clip members 11, 12, upon the brooch base member 14 is shown in rear elevation in Fig. 2. In Fig. 3, the clip member 12 is shown in assembly with and upon its pair of associated extensions 14b, 14c. Fig. 3 illustrates also an intermediate stage of association and likewise disassociation of the clip member 11 relative to its associated parts of the brooch base member 14. To disassociate an assembled clip member from the brooch base member, its clip back member is grasped and force applied, counter to the stated means of the clip member spring to displace its locking lugs 16b, 16b out of engagement with the associated locking recesses 14e, 14g.

I claim:

- 45 1. In a brooch assemblage, the combination of a plurality of clip members, each clip member comprising a resiliently related clip base member and a clip back member, and a brooch base member comprising a bar-like element, a thereto transversely extending element, and a pair of extensions connected to said transversely extending element, said pair of extensions being provided with locking recesses cooperating with parts of associated clip members aforesaid.
- 50 2. In a brooch assemblage, the combination of a plurality of clip members, each clip member comprising a resiliently related clip base member and a clip back member, and a brooch base member comprising a bar-like element, a thereto transversely centrally extending element, and a pair of extensions connected to said transversely extending element, said pair of extensions being

provided with locking recesses cooperating with parts of associated clip members aforesaid.

3. In a brooch assemblage, the combination of a plurality of clip members, each clip member comprising a resiliently related clip base member and a clip back member, and a brooch base member comprising a bar-like element, a thereto transversely extending element, and a pair of extensions connected respectively at right angles to said transversely extending element, said pair of extensions being provided with locking recesses cooperating with parts of associated clip members aforesaid.

4. In a brooch assemblage, the combination of a plurality of clip members, each clip member comprising a resiliently related clip base member and a clip back member, and a brooch base member comprising a bar-like element, a thereto transversely extending element, and a pair of extensions connected to said transversely extending element, said pair of extensions being provided with locking recesses cooperating with parts of associated clip members aforesaid, said extensions having flaring terminal portions.

5. In a brooch assemblage, the combination of a plurality of clip members, each clip member comprising a resiliently related clip base member and a clip back member, one of said related members carrying locking means, and a brooch base member comprising a bar-like element, a thereto transversely extending element, and a pair of extensions connected to said transversely extending element, said pair of extensions being provided with locking recesses cooperating with said locking means of its associated clip member.

6. In a brooch assemblage, the combination of a plurality of clip members, each clip member comprising a resiliently related clip base member and a clip back member, one of said related members carrying locking means, and a brooch base member comprising a bar-like element, a thereto transversely extending element, and a pair of extensions connected to said transversely extending element, said pair of extensions being provided with locking recesses cooperating with said locking means of its associated clip member, said extensions having flaring tapering terminals.

7. In a brooch assemblage, the combination of a plurality of clip members, each clip member comprising a resiliently related clip base member and a clip back member, resiliently arranged hinge means interconnecting said clip base member and said clip back member, and a brooch base member comprising a bar-like element, a thereto transversely extending element, and a pair of extensions connected to said transversely extending element, said pair of extensions being provided with locking recesses cooperating with parts of associated clip members aforesaid.

MARCEL BOUCHER.
